SHOE

Nicé D'Or, Union City, N. J.

Application June 12, 1957, Serial No. 46,571

Term of patent 14 years

(Cl. D7—7)

Fig. 1.

Fig. 2.

Fig. 1 is a side elevational view of a shoe embodying my new design; the side not shown is the same as that shown.

Fig. 2 is a rear elevational view of Fig. 1.

The dominant feature of my shoe design resides in the heel member of the configuration disclosed, which heel is attached to and maintained in spaced relationship from the sole by a pair of pegs, all as shown.

I claim:

The ornamental design for a shoe, as shown and described.
